FLYER

Andrew C. Adams, Sanford, N.C., assignor to Roberts Company, Sanford, N.C., a corporation of North Carolina

Filed May 1, 1961, Ser. No. 64,987

Term of patent 14 years

(Cl. D92—15)

FIG. 1

FIG. 3

FIG. 4

FIG. 2

FIG. 5

FIG. 6

FIGURE 1 is a front elevational view of a flyer embodying my new design;

FIGURE 2 is a bottom plan view taken substantially along the plane of line 2—2 of FIGURE 1;

FIGURE 3 is a right side elevational view of FIGURE 1;

FIG. 4 is a transverse sectional view taken substantially along the plane of section line 4—4 of FIGURE 3 showing the arm only, the other parts being omitted for convenience of illustration;

FIG. 5 is a fragmentary enlarged plan view of the flyer nose; and

FIGURE 6 is an enlarged partial perspective view of the terminal end of the presser foot.

I claim:

The ornamental design for a flyer, as shown and described.
